UNITED STATES PATENT OFFICE

AUGUST McDERMOTT, OF CABOT, PENNSYLVANIA

RAIL JOINT CHAIR

Application filed May 19, 1932. Serial No. 612,328.

My invention relates to improvements in rail joint chairs and it consists in the constructions, arrangements and combinations herein described and claimed.

5 It is an object of my invention to provide a rail joint chair which will receive the ends of abutting rails and which includes a wedge which provides a binding action between the webs of the rails, the underside of the heads and the flanges thereof to connect and retain the rails in abutting relation, without the use of bolts, spikes or similar fastening means.

10 It is also an object of my invention to provide a rail joint chair of a construction such as to permit the necessary longitudinal expansion and contraction between the securing wedge and rail members and yet maintain the rails in proper secure relationship with one another and the chair.

15 It is a still further object of my invention to provide a rail chair which will readily accommodate a bond wire, such as are employed to electrically connect abutting rail members.

20 Additional objects, advantages and features of invention will be apparent from the following description considered in conjunction with the accompanying drawing, wherein:

25 Figure 1 is a perspective view of my rail chair applied to abutting rail sections;

Fig. 2 is a top plan view thereof; and

30 Fig. 3 is a cross section on the line 3—3 of Fig. 2.

35 Referring to the drawing, the numeral 10 designates my rail joint chair, which in the present instance comprises a base 11 upon which the flanges 12 of the rails 13—13' rest. The base 11 is of considerably greater width than the flanges of the rails and is provided at the termination of the flanges with integrally formed shoulders 14 and 15. The shoulders 14 and 15 are undercut as at 16 and 17 so as to snugly engage the inclined upper surface of the rail flanges. The shoulder 14 extends the full length of the chair and is of a height to extend from the upper surface of the rail flange to a point immediately below the underface 18 of the rails 13—13'. The inner face 19 of the shoulder

14 is cut away to provide a longitudinally extending recess 20, for accommodation of a bond wire and fastening means presently to be described. The inner face 19 of the shoulder rests snugly against the web members 21 of the rails, and the exterior wall 22 may have any suitable contour which, in the present instance, is illustrated as inclined for a short distance and terminating in a vertical portion at the juncture with the base 11. 55 60

As is well understood, abutting rail ends are provided with bond wires whereby the rails will act as conductors for electric current for use in signalling systems and as clearly shown in Fig. 2 the bond wire 23 is connected 65 to the abutting rails as indicated at 23', the recesses 20 being so located as to accommodate the wire 23 therewithin. Thus, the bond wire is housed against the weather, as well as protected against tampering by unscrupulous persons or other causes which might effect disconnection of the bond wire. 70

The shoulder 15 also extends the full length of the rail chair and the undercut portion 17 lies flush with the upper surface of the adjacent rail flange 12, but the shoulder 15 stops short of the web members 21, of the rails. The face 24 of the shoulder is inclined downwardly and inwardly from its upper edge and is also beveled from one end to the 80 other end to accommodate a tapered wedge 25, now to be described.

The wedge is tapered as shown and is of a length equalling the length of the chair and has a lower angular base 26 to conform to 85 the upper surface of the rail flange 12, which it abuts, and also embodies a vertical straight edge 27 which engages the webs 21. The upper edge 28 is preferably straight and stops short slightly below the heads of the rails. 90 The outer face of the wedge, at its lower part is inclined as at 29 so as to snugly abut the face 24 of the shoulder 15.

The wedge 25 is provided with a transverse bore 30 formed adjacent one end thereof, and 95 the web 21 of the rail 13 is likewise provided with a bore 31, these bores being adapted for alignment when in assembled relation, to receive a dowel pin 32. The dowel pin is of a length to project beyond the web 21 into the 100

recess 20, and is apertured to receive a cotter pin 33.

The application of my chair to a rail will be readily understood from the following description thereof. Before the rails 13-13' are brought into abutting relation, the chair 10 is slid endwise upon one of the rail members so that the flanges 12 will rest upon the base 11. The rails 13-13' are now brought 10 into alinement, the bond wire 23 connected, and the chair 10 is moved longitudinally thereon until the meeting edges of the rails are approximately midway of the chair. The chair 10 is then secured to the usual ties (not shown) by spikes, as ordinarily practiced, the chair being provided with recesses 34, accommodating the heads of the spikes. With the parts positioned as described, the small end 35 of the wedge is inserted in the large 20 end defined by the tapered face 24, and driven firmly between the face 24, and the web 21, until the bore 30 of the wedge registers with the bore 31 of the web 21. The dowel pin 32 is next inserted through the alined bores and 25 finally, the cotter pin 33 is inserted in an aperture formed in the pin to secure it against withdrawal.

It should be noted that the dowel pin 32 secures the wedge 25 to the rail 13 only, there- 30 by permitting ready expansion and contraction between the rails 13-13', without reducing the efficient binding actions between the wedge 25 and the rail 13'.

I claim:

- 35 1. In a rail joint, a joint chair comprising a base having a central seat upon which two rails are adapted to rest, said base being provided with upwardly extending side shoulders, said shoulders being constructed to receive the base flanges of said rails, one of said shoulders having a face abutting the web of said rails and further having a longitudinal recess, said other shoulder stopping short of the web of said rails and having a tapered formation 40 throughout its length, a tapered wedge disposed between said last named shoulder and the web members of said rails, one of said web members having an aperture, said wedge having an aperture for registry with said first 45 named aperture, a dowel pin disposed within said apertures and projecting into said recess, and said dowel pin having an aperture in that portion disposed within the recess for reception of a cotter pin.
- 50 2. In a bonded rail joint, a joint chair comprising a base having a seat upon which two rails are adapted to rest, said base being provided with upwardly extending side shoulders, said shoulders having undercut portions 55 to receive the base flanges of said rails, one of said shoulders having a face abutting the web of said rails and further having a recess extending longitudinally throughout the length thereof to accommodate the bond of 60 said rails, said other shoulder stopping short 65

of the web of said rails and having a tapered formation throughout its length, a tapered wedge disposed between said last named shoulder and the web members of said rails, one of said web members having an aperture, 70 said wedge having an aperture for registry with said first named aperture, a dowel pin disposed within said apertures and projecting into said recess, and said dowel pin having an aperture in that portion disposed within the recess for reception of a cotter pin.

3. In a bonded rail joint, a joint chair comprising a base having a seat upon which two rails are adapted to rest, said base being provided with upwardly extending side shoulders, said shoulders having undercut portions to receive the base flanges of said rails, one of said shoulders abutting the web of said rails and further having a recess extending 85 longitudinally throughout the length thereof to accommodate the bond of said rails, wedge means cooperable with said other shoulder and the web members of said rails, said wedge having an aperture adjacent one 90 end thereof, one of said web members having an aperture for registry with said first named aperture, a pin disposed within said apertures and projecting into said recess, and said pin having an aperture in that portion disposed within the recess for reception of fas- 95 tening means.

AUGUST McDERMOTT.
